UNITED STATES PATENT OFFICE.

JOSEPH B. MERRIAM, OF MERIDEN, CONNECTICUT.

FIFTH-WHEEL.

SPECIFICATION forming part of Letters Patent No. 286,464, dated October 9, 1883.

Application filed December 26, 1882. (No model.)

To all whom it may concern:

Be it known that I, JOSEPH B. MERRIAM, of Meriden, in the county of New Haven and State of Connecticut, have invented a new Improvement in Fifth-Wheels; and I do hereby declare the following, when taken in connection with the accompanying drawings and the letters of reference marked thereon, to be a full, clear, and exact description of the same, and which said drawings constitute part of this specification, and represent, in—

Figure 1, a side view; Fig. 2, a top or plan view; Fig. 3, a vertical section; Figs. 4, 5, and 6, parts detached.

15 This invention relates to an improvement in that part of carriage running-gear commonly called the "fifth-wheel." In the usual construction this consists of two flat rings lying one upon the other, their flat surfaces 20 working together as the axle turns, and unavoidably producing a great amount of friction and resistance to the turning of the axle.

25 The object of this invention is to reduce this friction; and it consists in the introduction of a third ring between the upper and lower ring, the said third ring provided with anti-friction rolls, which take a bearing between the surface of the two principal rings, 30 the said third ring revolving concentric with the other rings, and arranged to revolve upon the same center, as more fully hereinafter described.

35 The lower ring, *a*, is constructed and arranged upon the axle in the usual manner. The upper ring, *b*, is also applied in the usual manner, the king-bolt *c* forming the center or axis upon which the rings rotate.

40 *d* is a third ring, of substantially the same diameter and thickness of the upper and lower rings, provided with spokes, or may be simply a central bar, *e*, as seen in Fig. 5, pierced at the center, as at *f*, to set upon the king-bolt, so as to revolve around the king-bolt concentric with the upper and lower rings. At 45 two or more points through an opening in the ring *d* rolls, wheels, or balls *g* are arranged, each upon an axis radial from the center or king bolt. These wheels *g* are in diameter greater than the thickness of the ring *d*, so 50 as to extend both above and below the ring, as seen in Figs. 1 and 2, and so that upon

the under side they will rest upon the lower ring, *a*, and above the ring *b* will rest upon the wheels; hence the said wheels take a bearing between the upper and lower ring, and roll between the two rings as the axle is turned. Because of the arrangement of the wheels in a third and independent ring, the wheels roll upon the surface of the lower ring, and the ring rides upon the wheel above; hence the 60 wheels traverse upon each ring but half the distance of the movement of the rings or axle, whereas if the anti-friction wheels were stationary—say in the lower ring—and so as to roll upon the lower ring, as in the previous 65 constructions of anti-friction wheels, the wheels must traverse the full movement of the lower ring in turning, and must therefore, if of the same diameter, make twice as many revolutions as do the anti-friction wheels arranged in 70 the third independent ring, as in this invention. The intermediate ring carrying the rolls is little less in thickness than the diameter of the rolls; hence the space between the upper and lower rings is so nearly full as to 75 prevent dirt or obstructions entering between the rings to interfere with the proper working of the rolls.

From the foregoing it will be understood that I do not broadly claim the arrangement 80 of the anti-friction rolls between the working-surfaces of the rings of a fifth-wheel, the essential feature of my invention being the intermediate ring between the upper and lower rings, and which carries the rolls in recesses 85 prepared for them, and whereby the surface of the rings is protected from dirt or other obstruction to the proper working of the roll; but

What I do claim is—

90 The combination of the upper and lower rings of a fifth-wheel with an intermediate ring of equal diameter, constructed with recesses through it, and rolls arranged in said recesses to ride upon the lower ring and support the upper ring, the said intermediate ring hung upon the king-bolt as its center, 95 substantially as described.

JOSEPH B. MERRIAM.
